UNITED STATES PATENT OFFICE

135,564

DESIGN FOR A BREAD SLICING BOARD

Sam F. Townsley, Memphis, Tenn.

Application February 17, 1943, Serial No. 109,560

Term of patent 3½ years

To all whom it may concern:

Be it known that I, Sam F. Townsley, a citizen of the United States, residing at Memphis, in the county of Shelby and State of Tennessee, have invented a new, original, and ornamental Design for a Bread Slicing Board, of which the following is a specification, reference being had to the accompanying drawing, forming part hereof.

Figure 1 is a top plan view of a bread slicing board, showing my new design.

Figure 2 is a side elevational view thereof.

Figure 3 is an end elevational view looking at the left end in Figure 2.

Figure 4 is an end elevational view looking at the right end in Figure 2.

I claim:

The ornamental design for a bread slicing board, as shown.

SAM F. TOWNSLEY.
